UNITED STATES PATENT OFFICE.

OSCAR FERN, OF NEWBURYPORT, MASSACHUSETTS.

SHANK STIFFENER FOR SHOES.

Application filed September 16, 1925. Serial No. 56,712.

To all whom it may concern:

Be it known that I, OSCAR FERN, a citizen of the United States, and a resident of Newburyport, in the county of Essex and State

5 of Massachusetts, have invented an Improvement in Shank Stiffeners for Shoes, of which the following is a specification.

This invention relates to that type of shank stiffeners for turn shoes, in which a 10 metal reinforcing strip is attached to a leather or leather board stiffener, which usually extends from the back end to the ball of the shoe, and more particularly to certain improvements on the type of reinforcing 15 strip shown in my prior Patent No. 1,517,719, of Dec. 2nd, 1924.

In the practical application of the device 20 of my said patent to a turn shoe, by ordinary shoe factory operations, several difficulties were encountered, particularly in that the supplemental reinforcing strip, which is located between the main reinforcing strip and the stiffener piece was liable to become somewhat misplaced previous to 25 the beating-out operation, at which time the prongs, which are formed with the supplemental reinforce, are driven into the outer sole and clenched. In consequence the prongs were frequently not driven perpendicularly into the sole, but were liable to be 30 driven at an inclination thereto, and, in consequence the stiffener was not securely attached to the sole. I have ascertained that this difficulty was primarily due to the fact 35 that, in practice, it is necessary to attach the main reinforcing strip to the stiffener piece before the latter is placed in the shoe and, as the reinforcing strip is attached at its ends to the stiffener piece, the latter was 40 liable to spring away from the former, permitting the supplemental reinforce to move from the position in which it is intended to be held seated in the main strip, so that, when the shoe was relasted, previous to the 45 beating out operation, frequently the supplemental reinforce was not pushed back into the position, in which it should be held, with the consequent result above noted.

The object of my invention is to improve 50 the construction of my said prior patent by providing means whereby the supplemental reinforce will be securely held in such a position, previous to the insertion of the stiffener into the shoe, that, when the shoe is relasted, the supplemental reinforce will seat 55 in the position intended in the main rein-

force and will be securely held in this position while the final operation of attaching the stiffener to the outersole is being performed.

I accomplish this object in the manner hereinafter described, and as illustrated in the accompanying drawing, in which:

Fig. 1 is a longitudinal sectional view of the shank portion of a shoe provided with shank stiffening means embodying my invention.

Fig. 2 is a bottom view of the shank stiffener parts assembled ready for insertion in a shoe.

Fig. 3 is a sectional view at line 3—3 of Fig. 2, on an enlarged scale.

Fig. 4 is a sectional view at line 4—4 of Fig. 2.

Figs. 5 and 6 are perspective views of the parts of the shank stiffener reinforcing means.

As shown in the drawing the stiffener comprises the leather, or leather board shank stiffener piece *b*, of ordinary form, which fits the bottom of the shoe from the heel end to the ball portion thereof, and to the under side of which the main reinforce, or metal reinforcing strip *c* is attached by a pair of prongs *d* at each end, which are driven therein, said reinforce being of the usual transversely concave, or somewhat U-shaped form and being provided with an additional prong *d'* at its heel end, which extends oppositely to the prongs *d* and is adapted to be driven into the outer sole beneath the heel, when the stiffener is attached to the outersole *a*. The supplemental reinforce, or metal strip *e*, is adapted to fit into the middle portions of the main reinforce and has end prongs *f* which are adapted to extend through apertures in the main reinforce, as described in my said prior patent.

According to my invention, the supplemental reinforce *e* is provided with a pair of integral prongs *g* at the middle of the longitudinal edges of the sides thereof which project oppositely to the prongs *f*, so that, when the main reinforce is attached to the stiffener piece *b*, the prongs *g* will be driven into the middle portion of the stiffener piece *b*, and clenched therein, as indicated on Fig. 3, thereby securely attaching the supplemental reinforce to the middle portion of the stiffener piece.

As thus arranged, the main and supplemental reinforce members will be held in

fixed relation with each other, and with the stiffener piece, so that, when the whole stiffener, as thus assembled, is inserted in the shoe, the supplemental reinforce will be so held that its prongs *f* will project perpendicularly to the stiffener piece, and will therefore be driven perpendicularly into the outer sole and be clenched therein in the position intended. At the same time the middle portion of the stiffener piece *b* will be securely connected at its middle portion to the outer sole, so that any tendency of the stiffener to spring up within the shoe is prevented and the entire shank portion of the shoe is bound together at its middle as well as at each end.

I claim:

1. In combination with a main metal reinforcing strip for a shoe shank stiffener having means at its ends for attaching it at its upper side to the under side of the stiffener and a pair of intermediate apertures, a supplemental metal reinforcing strip disposed between the stiffener and said main strip and having two pairs of oppositely extending prongs formed therewith, one pair extending into the stiffener and the other pair extending through said apertures in position to be driven into the outer sole of the shoe in which it is placed.

2. In combination with a main reinforcing strip for a shoe-shank stiffener having its intermediate portion shaped to form a con-

cave upper side and a convex under side and having means projecting at each end from the upper side attaching the same to the stiffener, a correspondingly shaped supplemental metal reinforcing strip having its convex side seated in the concave side of said main strip and having two pairs of oppositely projecting prongs formed therewith, one pair being located at the middle portion of the longitudinal edges and extending into the stiffener, and the other pair being located at its middle and extending through said main strip in position to penetrate the outer sole of the shoe.

3. In combination with a main reinforcing strip for a shoe-shank stiffener having a U-shaped intermediate portion provided with a pair of suitably spaced apertures in the middle line thereof and right angularly disposed prongs projecting from each end thereof at its concave sides, a similarly U-shaped supplemental metal reinforcing strip nested in the intermediate portion of said main strip and having an integrally formed prong projecting from the middle of each side edge thereof and extending into and clenched within the stiffener and having an integrally formed prong at each end extending through said apertures and adapted to be clenched in the sole of the shoe.

In testimony whereof, I have signed my name to this specification.

OSCAR FERN.
